TALIAFERRO P. SHAFFNER, OF LOUISVILLE, KENTUCKY.

Design No. 3,366, dated February 9, 1869.

DESIGN FOR A TRADE-MARK.

The Schedule referred to in these Letters Patent and making part of the same.

To all whom it may concern:

Be it known that I, TALIAFERRO P. SHAFFNER, of Louisville, in the State of Kentucky, have invented a certain new Design for a Trade-Mark; and I declare that the same is correctly represented in the accompanying print, which is made a part of this specification.

I claim, and desire to secure by Letters Patent—
The design for a trade-mark, substantially as herein set forth.

TAL. P. SHAFFNER.
